(57) **CLAIM**

The ornamental design for a portion of a front panel for an electronic device, as shown and described.

DESCRIPTION

FIG. 1 is a perspective view, from the front and above, of a portion of a front panel for an electronic device in accordance with a first embodiment of the present invention; FIG. 2 is a front view thereof; and,

FIG. 3 is a perspective view, from the front and above, of a second exemplary embodiment of the present invention, which differs from the first embodiment in that the lens is translucent.

The broken lines shown in FIGS. 1-3 represent environmental subject matter and form no part of the claimed design. The rear, top, bottom, left side and right side views are omitted and form no part of the claimed design.
